United States Patent Office

Des. 179,884

Patented Mar. 19, 1957

179,884

HOUSING FOR COIN CONTROLLED DISPENSING MACHINE OR SIMILAR ARTICLE

Harold W. Darr, Minneapolis, Minn., assignor to Refrigeration Engineering Company, Montgomery, Minn., a corporation of Minnesota

Application June 17, 1955, Serial No. 36,558

Term of patent 7 years

(Cl. D52—3)

Fig. 1 is a view in perspective of a housing for coin controlled dispensing machine or similar article, as seen from the front and one side, and showing my new design; and

Fig. 2 is a view in perspective as seen from the opposite side and back.

I claim:

The ornamental design for a housing for coin controlled dispensing machine or similar article, as shown.
